TEA BAG OR THE LIKE AND METHOD OF
AND MEANS FOR SECURING ITHarold W. Morris, Waltham, Mass., assignor to
Frederick Osann Company, New York, N. Y.,
a corporation of New YorkOriginal application July 18, 1929, Serial No.
379,107, now Patent No. 1,875,753. Divided and
this application July 26, 1930. Serial No.
470,873

11 Claims. (Cl. 53—3)

This invention relates to the wrapping or tying of material together in bundle formation. While this invention is not limited thereto in its broader aspects, one example is in the packaging of portions of tea in pieces of muslin or the like to form what is known as "tea balls", the tea being placed substantially in the center of the piece of muslin and the margins of the piece being brought together so as to form a bag loosely enclosing the tea and secured by a wrapping or tying operation. This invention also includes the product so wrapped.

The present application is a division of my application Serial No. 379,107, filed July 18, 1929, for Mechanism for securing bags or the like which has matured into Patent Number 1,875,753.

The wrapping or tying operation may be performed by a sewing machine of a type commonly used for sewing on buttons. In such machines the button is commonly held in a clamp to present a hole therein in the path of a needle and between sewing strokes of the needle a relative movement laterally of the needle path between the needle and the clamp is produced so that the needle passes alternately through each of a pair of sewing holes in the button. In some machines this relative lateral movement is produced by moving the button clamp and in other machines it is produced by moving the needle laterally either bodily or about a pivot. Commonly these machines are of the single thread chain type, although a lock stitch two-thread machine might be used if desired.

In accordance with the present invention any of these button sewing machines may be used by substituting for the button clamp a holder for the bag (or other material to be wrapped) so related to the needle that during the stitching operation the needle passes alternately on opposite sides of the bag material which is gathered together to form a bundle where the stitching is effected, thus to tie or wrap the material of the bag together locally by a series of thread loops passed alternately around the bag material at one place on opposite sides and secured therebeneath. Both sides of each loop pass together about the gathered material and the ends of successively placed loops are secured together. Some of these stitch loops, particularly those first placed may pass through portions of the bag material which may chance to bulge into the needle path, this engagement of the loops with the material acting to hold the threads against displacement therealong. This method of wrapping thread loops about the fabric may find application where-

ever it is desired to wrap about material gathered together in bundle formation.

For a more complete understanding of this invention reference may be had to the accompanying drawing in which

Figure 1 is a side elevation of a button sewing machine, the side cover plate being removed, showing a bag holder substituted for the button clamp.

Figure 2 is a perspective of the bag holder.

Figure 3 is a cross section of the bag holder showing a bag in position therein.

Figure 4 is a side elevation of the upper jaw member of the bag holder.

Figure 5 is a detail section on line 5—5 of Figure 1.

Figure 6 is a perspective of the completed tea ball.

Figure 7 is a detail to a larger scale showing the engagement of the thread loops about the fabric of the ball.

Referring to the drawing, the sewing machine shown in Figure 1 is substantially that shown in the Lyons Patent No. 1,671,197, granted May 29, 1928, in which a laterally movable needle is employed, the needle vibrating laterally about a pivot. It should be understood, however, that the invention is not limited to this type of machine, which is shown only by way of example.

The machine as shown in Figure 1 comprises a suitable base 1 having a sewing arm 2 upstanding from the rear portion of the base and extending thereover toward the front of the base where it is provided with the sewing head 3. Beneath this sewing head is positioned the work table 4 which is provided with a suitable opening 5 therethrough through which the needle 6 may pass. The needle 6, as shown, is carried at the lower end of a needle bar 7 slidable through guides 8 and 9 carried by the head 3, the upper guide being carried by the pivot 10. The lower guide 8 is pivoted to the forward end of a lever 12 having an adjustable fulcrum at 13 by which the amount of lateral motion of the needle may be adjusted, the rear end of this lever 12 having a cam follower 14 riding in a cam groove in a horizontal cam 15. This cam 15 is carried at the upper end of a rotary shaft 16 which is driven from the horizontal shaft 17 which has suitable driving means (not shown) attached thereto. The shaft 17 also carries an eccentric 18 by which motion is transmitted through an eccentric rod 19 to a rock shaft 20 through a crank arm 21 on its rear end. The forward end of this rock shaft 20 is connected through the crank arm 22 and the

85

90

95

100

105

110

link 23 with a collar 24 adjustably clamped to the needle bar 7. By means of these driving connections the needle bar is caused to reciprocate to impart sewing strokes to the needle, and it is 5 also caused to move laterally alternately in opposite directions between sewing strokes. At the forward end of the shaft 17 is carried some form of looper mechanism shown conventionally as a rotary looper 25, this looper forming a portion 10 of the stitching instrumentalities in position to cooperate with the needle 6 and to form chain stitches, this machine being a single thread chain stitch machine.

The arm 2 is shown as provided adjacent to its 15 lower end with suitable pivot lugs 30 designed to receive the button clamp when this machine is used for sewing buttons. When used for the purpose of the present invention, these pivot lugs are employed to pivotally secure the rear end portion 20 of a work holder 31. This work holder, as shown, comprises a plate portion 32 having secured at its rear end a pivot block 33 adapted to receive a pivot pin 34 for pivotally connecting the work holder to the lugs 30. The forward end 25 of the plate portion 32 is so positioned as to normally rest upon the upper face of the work table 4 and carries thereon a pair of upwardly extending elements 35 and 36 spaced apart a distance sufficient to permit portions of a sheet of muslin 30 or other suitable material, such as 40, gathered together in bundle formation and, as shown, enclosing a portion of tea or other desired commodity, to be inserted therebetween. These elements 35 and 36 are provided with opposed 35 grooves 41 and 42 in their confronting faces which form passages to receive the needle 6 outwardly of opposite sides of the gathered fabric material 40 positioned therebetween.

As shown the element 35 is narrower and of 40 less height than the element 36, the element 36 thus serving as a guide against which the fabric material may be pressed and then guided down into its position between the two elements thus to facilitate the insertion of the material into 45 the holder. The forward and rear opposing faces of these elements are preferably beveled, as shown at 43 and 44, in order also to facilitate the easy placing and removal of the fabric material. The fabric thus gathered together into bundle 50 formation is arranged to be clamped in position between the elements 35 and 36. To this end a pivot block 50 is shown as fixed to the plate 32 to the rear of an upwardly bent portion 51 thereof, and to the side of this plate is shown as pivoted at 52 a clamping member 53. The forward end of this clamping member is shown as formed as an angle plate 54 which may, when idle, rest upon the spaced upper end portions 55 of the element 36, and which has a pair of spaced downwardly extending feet 57 arranged in a line substantially at right angles to the aligned relation of the elements 35 and 36, and on opposite sides of the needle path. The upper face 60 of the member 54 is cut away as at 61 in continuation 65 of the space between the feet 57 to permit the needle to pass freely therebetween. This member 54 is fixed as by means of the bolts 62 to the rear portion of the clamping member which as shown has an upward and rearward laterally bent rear extension 66.

Sewing machines of this type commonly have means for lifting the button clamp from the work table. The machine shown has such a mechanism in the rock shaft 70 pivoted in bearings 71 and 72 in the upper portion of the arm

2, this rock shaft 70 having a crank arm 73 to which is attached a chain 74 to the lower end of which the button clamp may be fixed. The shaft 70 may be rocked against the action of a torsion spring 75 by any suitable means, such for example, as a treadle as disclosed more particularly in the Lyons patent hereinbefore referred to. Where the work holder hereinbefore described is employed, this chain 74 may be fixed thereto, as, for example, on the pivot 52 so that the work holder may be raised from the face of the work table, and this raising of the work holder may be utilized to lift the clamping member 53 from engagement with the fabric placed between the elements 35 and 36. To this end there may be fixed to the lower portion of the machine, an arm 80 having a slotted extremity in which the laterally turned end 66 of the clamping member may be engaged so that as the work holder is raised the clamping feet are caused to be swung upwardly at a faster rate than the work holder, due to the fact that the rear end of the clamping member is prevented from rising with the work holder by reason of its engagement with the fixed plate 80. In order that the normal clamping position of the feet may be adjusted in accordance with the size of the bundle of fabric, this arm 80 may be adjustable. As shown this may be accomplished by forming this arm in two parts having a pin and slot connection with each other as at 82 (see Figure 5). The lower ends of the feet 57 are preferably provided with teeth or prongs 85, those of each foot being directed away from those of the other foot so as to tend to stretch the material lengthwise between the elements 35 and 36 when the feet are brought down thereon. The element 36 also acts as a stop to limit the descent of the clamping member when no work is in the holder, thus protecting the prongs 85 from contacting with and being dulled by metal parts of the holder.

The bag having been formed and the margins of the fabric material having been brought together in bundle formation and inserted in the work holder between the elements 35 and 36 while the forward end of the work holder is in its raised position, the work holder is allowed to descend to the face of the work table which brings the feet of the clamp down against the work. The stitching operation is then performed, the needle passing in its stitching strokes alternately through the passages formed by the notches 41 and 42 in the elements 35 and 36 so as to lay thread loops alternately over and down opposite sides of the fabric, these loops being engaged beneath the fabric in chain stitch formation by reason of the looper mechanism hereinbefore referred to. As is usual in button sewing machines of the single thread type, the last two strokes of the needle may be caused to take place in the same lateral relation between the needle and the work, thus to tie the thread at the end of the sewing operation. Then the operator raises the work holder, which acts to break the thread adjacent to the knot as well as to lift the clamping member, whereupon the tea ball may be removed from the machine, and another which has not been tied placed in position therein.

In Figure 7 is shown somewhat diagrammatically for the sake of clarity, the lower face of the bundle of fabric where the successive stitches are secured together in chain stitch formation, the successive stitches as placed being repre-

sented by *a*, *b*, *c*, *d*, and *e*, respectively. Of course in actual operation these thread loops are tightly engaged with each other in usual chain stitch formation. It is, of course, evident that were 5 this work holder applied to a two-thread machine, the thread loops would be interlocked with a second thread on the under side of the fabric bundle in the well known manner of a lock stitch.

10 Certain embodiments of this invention having thus been described, it should be evident to those skilled in the art that various changes and modifications may be made therein without departing from the spirit or scope of this invention as defined by the appended claims.

15 I claim:

1. A wrapping for a bundle which comprises a series of loops of thread passed over and about opposite sides of the bundle at one place and sealed together in chain stitch formation.

20 2. A bag having a portion gathered together and secured by loops of thread passed therearound and secured together in chain stitch formation.

25 3. In combination, fabric material gathered together and secured by loops of thread passed therearound and secured together in chain stitch formation.

40 4. In combination, fabric material gathered together and secured by loops of thread passed therearound and secured together in chain stitch formation, certain of said loops passing through portions of the fabric.

45 5. A wrapping for a bundle which comprises a series of loops of thread, both sides of each loop passing together locally about the bundle, alter-

nate loops extending therearound in opposite directions and their ends being secured together.

6. A bag having a portion gathered together and secured by a series of loops of thread, both sides of each loop passing together therearound and alternate loops in opposite directions and with their ends secured together.

7. A bag having a portion gathered together and secured by a series of loops of thread, both sides of each loop passing together therearound, the ends of certain successive loops being secured together, and certain of said loops passing through portions of the bag.

8. In combination, fabric material gathered together and secured by a series of loops of thread, both sides of each loop passing together therearound and successive loops being secured together at their ends, certain of said loops passing through portions of the fabric.

9. In combination, fabric material gathered together and secured by a series of loops of thread, both sides of each loop passing together therearound, alternate loops passing in opposite directions about the material and having their ends secured together.

10. A wrapping for a bundle which comprises a series of loops of thread wrapped therearound locally, both sides of each loop passing together about the bundle and successive loops being secured together at their ends.

11. A bag having a portion gathered together and wrapped by a series of loops of thread passed therearound, both sides of each loop passing together about the gathered portion, successive loops being secured together.
